UNITED STATES PATENT OFFICE

94,788

DESIGN FOR A SCROLL SAW FRAME

Herbert E. Tautz, Milwaukee, Wis., assignor to
Delta Manufacturing Company, Milwaukee,
Wis.

Application October 3, 1934, Serial No. 53,471

Term of patent 14 years

To all whom it may concern:

Be it known that I, Herbert E. Tautz, a citizen of the United States, residing at 3775 North Holton Street, city of Milwaukee, in the county of Milwaukee and State of Wisconsin, have invented a new, original, and ornamental Design for Scroll Saw Frames, of which the following is a specification, reference being had to the accompanying drawing, forming part thereof.

The figure is a perspective view of a scroll saw frame, embodying my new design.

I claim:

The ornamental design for a scroll saw frame, as shown.

HERBERT E. TAUTZ.
